UNITED STATES PATENT OFFICE.

JOHANNES HARTSTRA, OF GRAND RAPIDS, MICHIGAN.

WEATHER STRIP.

Application filed November 11, 1919. Serial No. 337,164.

To all whom it may concern:

Be it known that I, JOHANNES HARTSTRA, a subject of Holland, and declarant to become a citizen of the United States, residing at Grand Rapids, in the county of Kent and State of Michigan, have invented new and useful Improvements in Weather Strips, of which the following is a specification.

This invention relates to improvements in weather strips and the principal object of the invention is to provide means for preventing the entrance of water at the bottom of the inwardly swinging sash.

Another object of the invention is to provide means for draining the water caught by the strip therefrom.

Hitherto it has been impossible to prevent inwardly swinging casement sashes from leaking at the sill and for this reason this style of window has not met with favor in spite of its many advantages over the vertically movable sash. It is the purpose of my invention to provide metal strips for these windows which will catch any water passing through them and which are provided with means for draining the water on to the outer part of the sill.

The invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a sectional perspective through a window supplied with my invention and showing a sash swung open.

Figure 2 is a vertical section with the sash closed.

Figure 3 is a sectional perspective with the window closed.

Figure 4 is a plan view of the bottom strip.

In these views 1 indicates the window frame, 2 the outside sill and 3 the inside sill. The sash 4 is hinged to the frame, as shown, so that it will swing inwardly. The bottom of the sash is recessed at its outer edge to receive a part of the upper section 5 of the device. This section is of substantially angular-shape with one part screwed to the outer face of the sash and the other

part screwed to the upper wall of the recess. The vertical part is formed with the projection 6 which has a long inclined upper face, a short slightly curved lower face and with the outer edges of the two faces connected together by a vertical part. The water will run down the upper face of the projection and will drop off the ridge formed by the junction of the vertical part with the curved under face. The horizontal part of the section, which lies within the recessed part of the sash, is provided with a substantially wedge-shaped projection 7, the outer face of which is flat.

The other section 8 of the device is seated upon a plate 9' which rests on the sill 2. This section 8 is of hollow construction and is provided with a pair of upwardly extending ribs 9 which are spaced apart to form a trough 10. The inner rib is of less height than the outer rib and this inner rib is provided with a vertical inner face against which the extreme lower edge of the sash abuts when the sash is closed. The upper end of the outer rib is provided with an offset part having a flat inner face against which the outer face of the projection 7 abuts when the window is closed. It will be seen that the inner face of this offset part overhangs the trough. The bottom of the trough is provided with spaced openings 11 which lead into the interior of the section so that any water dropping to said trough will drain into the section. The lower outer edge of said section is provided with openings 12 through which the water may flow from the section onto the outer sill 2. The section 8 and plate 9' are secured to the sill by the screws 13 which pass through both the sections and the plate, as shown. The plate 9' is formed with wedge-shaped projections 14 which extend across the same in rear of the openings 12 for directing the water flowing from the trough to said openings.

It will be seen that the water passing down the sash will flow over the projection 6 and will drip from the projection on to the rounded outer face of the section 8 and from this section it will flow on to the sill. If the wind is blowing some of the water dripping off the projection 6 may be forced by the wind between the upper end of the outer rib 9 and the projection 7. In this case the water will drip from the lower end of the projection 7 into the trough and will

pass from the trough into the section 8 and will pass from the section 8 through the openings 11. On account of the length of the projection 7 and the space between its 5 lower end and the trough 10 water will tend to drip from the projection 7 into the trough 10 and will drain from the trough 10 through the opening 11, and in consequence the liability of water finding its way to the 10 inner sill 3 will be lessened. This device will also act to prevent the wind from passing under the bottom of the sash.

It is thought from the foregoing description that the advantages and novel features 15 of my invention will be readily apparent.

I desire it to be understood that I may make changes in the construction and in the combination and arrangement of the several parts, provided that such changes fall within 20 the scope of the appended claims.

What I claim is:—

1. A device of the class described comprising an upper section adapted to be affixed to the outer face of a swinging sash and 25 having a pendent water deflecting projection thereon and also having a lower pendent projection with a flat outer face arranged in rear of the first-named projection, a lower section adapted to be fixed upon an 30 outer sill and having a pair of upwardly extended spaced ribs, one to engage the wall of a rabbet at the lower edge of the sash

and the other to engage or abut against the flat face of said lower and rear projection, and a trough between said ribs, said trough 35 having drain holes therein.

2. Weather excluding means for use in connection with a swinging sash and the outer and inner sills of a window frame, said means comprising a member adapted to be 40 applied to the outer face of a sash at the lower rabbetted end thereof, and a second member adapted to be superimposed upon and fixed to the upper side of the outer sill, the first-named member being provided 45 with a projection pendent from the upper wall of the rabbet and with a projection disposed in front of the outer face of the sash, and the second named member being provided with an upwardly extending projection 50 to be opposed to the upright wall of the rabbet, and a second-projection extending above and spaced from the first-named projection to abut against the face of the first named projection of the first-named 55 member, the two projections of the second-named member forming between them a trough having drain openings into the second-named member and the second-named member further having openings in its outer 60 wall.

In testimony whereof I affix my signature.

JOHANNES HARTSTRA.
